UNITED STATES PATENT OFFICE.

ANTONIO CARLOS BRAZIL, OF RIO DE JANEIRO, BRAZIL, ASSIGNOR TO COMPANHIA
GRELHAS ECONOMICAS BRASIL, A CORPORATION.

GRATE AND GRATE-BAR.

1,272,906.

Specification of Letters Patent. Patented July 16, 1918.

Application filed January 29, 1918. Serial No. 214,384.

To all whom it may concern:

Be it known that I, ANTONIO CARLOS BRAZIL, a citizen of the Republic of the United States of Brazil, residing at Rio de Janeiro, 5 United States of Brazil, have invented certain new and useful Improvements in Grates and Grate-Bars; and I do hereby declare the following to be a full, clear, and exact description of the invention, such as will 10 enable others skilled in the art to which it appertains to make and use the same.

My invention consists of certain improvements in and relating to grates and grate bars, and it is intended to provide a grate 15 which is not apt to clog up from ashes, cinders, clinkers and other residue, but which, if clogged up, may be readily cleaned without the use of slice bars or other tools ordinarily employed for this purpose.

20 The invention is also intended to provide a grate bar which has great wearing properties, and which is especially adapted to the rough usage to which such bars are necessarily subjected.

25 My invention will be more fully understood after reference to the accompanying drawings, in which similar reference symbols indicate corresponding parts in the several views, and in which:—

30 Figure 1 shows a side elevation of the grate bar constructed according to my invention.

Fig. 2 is a plan view showing a series of bars assembled to form part of a grate.

35 Fig. 3 is an end view showing three of the bars of Figs. 1 and 2, the parts being shown on a larger scale than in said figures.

Fig. 4 shows a section along the line 4—4 of Figs. 1 and 2, the parts being shown on 40 the same scale as in Fig. 3.

Fig. 5 shows one of the bars mounted in the grate of the furnace, with means for shaking the same, parts being broken away.

Fig. 6 shows an end view of a series of 45 bars mounted to form a grate with the shaking attachment removed.

Fig. 7 is a similar view to Fig. 6, but shows a section along the line 7—7 of Fig. 5, and looking in the direction of the arrows.

50 Fig. 8 shows a modified form of grate bar in which the pivot is near the top of the bar.

Fig. 9 shows three of the bars of Fig. 8 as assembled in the grate, but as seen from the left of said figure.

Fig. 10 is a similar view to Fig. 9, but 55 shows a modified form of grate bar; and

Fig. 11 is a similar view to Fig. 7, but shows an arrangement whereby alternate bars are rocked or shaken through a limited 60 arc and then all of the bars are shaken simultaneously.

Referring first to Figs. 1 to 7, A represents a grate bar having its body portion *a* provided with pivots *a'* adapted to rest in sockets *b* in the walls *B* of the grate; and 65 also provided with pins *a*² projecting from the bosses *a*³, which pins are adapted to engage the shaking apparatus, as will be hereinafter described.

The bars may also be provided with spacing lugs *a*⁴ to prevent the warping or bending of the bars laterally when in use. These bars are preferably of the general shape in cross section, as shown in Fig. 4, in which the bar is curved at the top, as at 1, and 75 is widest near its upper end, as at 2, and tapered outward terminating in the curved bottom 4.

The individual bars constituting the grate have their pivots *a'* supported, as at *b'*, in 80 the walls of the grate as shown in Figs. 5 and 6, and the bars are rocked or shaken about these pivots in any suitable way, as by means of the plate *D*, pivoted as at *d* to the outside bar of the grate and having 85 notches *d'* engaging the pins *a*² of the other bars.

This plate *D* is provided with a rack *d*² engaging the segmental gear *E* having teeth *e*, which gear is fast on the shaft *F* rotated 90 by the hand crank *G*. The segmental gear *E* is pivoted eccentrically, as shown in Fig. 7, so that the teeth *e* may remain in engagement with the rack *d* on the plate *D* as said plate is swung from the center in either 95 direction, as indicated in dotted lines in Fig. 7.

I have shown in Figs. 1 to 7 the pivots *a'* of the grate bars located at a short distance below the top of the bar, but under certain 100 conditions it may be preferable to have these pivots arranged at the top of the bar *A'* as shown in Figs. 8 and 9.

With this construction it will be less difficult to shake the bar. The bar may be used 105 with high grades of coal, such as Cardiff coal, but with coal that has much cinder or gives much clinker I find that lowering the

support helps to move the bottom layer of coal when cleaning the fire.

I have shown in Figs. 1 to 9 the top of the grate bar rounded, as at 1, while the 5 top of the bar A² of Fig. 10 is shown as having a sharper point, as at 1^a, but the shape of the grate at the top of the bar may be varied at will; but I prefer a full rounded curve of the general character of 10 that shown in Figs. 1 to 9 because such a shape is not so apt to burn out as where the lines are finer.

It will be seen that the tapered head of the bar shown in Figs. 1 to 10 will form 15 wedging faces to engage the coal, and the bars may be spaced farther apart, or wider air passages may be provided than with the forms of grate now generally used.

Instead of simultaneously shaking all of 20 the bars after the manner indicated in Fig. 7, it may be more convenient and require less power to shake alternate bars only, or to shake alternate bars through a greater angle than the bars therebetween. Such an 25 arrangement is provided for in the construction shown in Fig. 11, in which the pins a² of alternate bars project into bearings in the shaker plate D', while the pins of the other 30 bars project into elongated slots d⁰ which permit the shaker plates D' to have a considerable lateral play in either direction before the pins projecting into these elongated slots d⁰ bring up against the end walls thereof.

35 With the construction shown a considerable shaking motion may be imparted to alternate grate bars without disturbing the bars located therebetween, while a violent shaking will cause all of the bars to be 40 rocked about their pivots.

The shape of the bars herein described will enable the bars to be placed farther apart in the grate, providing wide passages therebetween for the influx of air, and the 45 air coming in slowly at the bottom of the bar gains speed as it passes through the narrow part of the passage between the bars and then spreads out again toward the tops of the bars distributing it through the fuel 50 resting on the bars. This therefore affords a better draft for the air than where the fuel is located directly above the narrowest part of the air passage.

By having the bars with rounded edges 55 there are no sharp corners to burn, and the bars will last much longer. As the grate may be cleaned by shaking the grate bars, the necessity for the use of slice bars is avoided.

60 It will be obvious that various modifications might be made in the herein described device, and in the construction, combination and arrangement of parts which could be used without departing from the 65 spirit of my invention.

Having thus described my invention what I claim and desire to secure by Letters Patent of the United States is:—

1. A grate comprising a plurality of grate bars each having a cross section substantially in the form of two wedges with their larger ends abutting, and the ends of the wedges rounded, each bar being provided with a pivot lug at each end thereof, and with a cylindrical spacing lug intermediate 70 of said ends and coaxial with its pivots, with means for rocking said bars about said lugs, substantially as described.

2. A grate comprising a plurality of grate bars each having a cross section substantially in the form of two wedges with their larger ends abutting, and the ends of the wedges rounded, each bar being provided with a pivot lug at each end thereof, with a shaking pin below said pivot lug, and 80 with a cylindrical spacing lug intermediate of said ends and coaxial with its pivots, with a shaking plate connected to said pins, and means for imparting a vibratory motion to said plate, substantially as described. 85

3. A grate comprising a plurality of grate bars each having a cross section substantially in the form of two wedges with their larger ends abutting, and the ends of the wedges rounded, each bar being provided with a pivot lug at each end thereof, with a shaking pin below said pivot lug, and with a cylindrical spacing lug intermediate 95 of said ends and coaxial with its pivots, with a shaking plate connected to said pins, 100 and means for imparting a vibratory motion to said plate, comprising rack teeth on said plate and a segmental gear wheel engaging said rack teeth, a spindle for said gear wheel secured eccentric thereto, and 105 means for rocking said spindle, substantially as described.

4. A grate comprising a plurality of grate bars each having a cross section substantially in the form of two wedges with their 110 larger ends abutting, and the ends of the wedges rounded, each bar being provided with a pivot lug at each end thereof, with a shaking pin below said pivot lug, and with a cylindrical spacing lug intermediate of 115 said ends and coaxial with its pivots, with a shaking plate connected to alternate pins and provided with slots into which the other pins project, these slots having end walls adapted to bring up against the corresponding pins when the plate is vibrated through a sufficient distance, with means for imparting a vibratory motion to said plate, whereby the groups of alternate grate bars are 120 rocked through different angles, substantially as and for the purpose described.

5. A grate bar having a cross section substantially in the form of two wedges with their larger ends abutting, and the ends of the wedges rounded, said bar being pro- 130

vided with a pivot lug at each end thereof, and with a cylindrical spacing lug located between said pivot lugs and coaxial with said pivot lugs, substantially as and for 5 the purposes described.

6. A grate bar having a cross section substantially in the form of two wedges with their larger ends abutting and the ends of the wedges rounded, said bar being provided with a pivot lug at each end thereof, and with a shaking pin below said pivot 10

pin, and with a cylindrical spacing lug located between said pivot lugs and coaxial with said pivot lugs, substantially as and for the purposes described.

15

In witness whereof I have hereunto set my hand in the presence of two witnesses.
